UNITED STATES PATENT OFFICE

169,421

DOUBLE BOILER ADAPTER RING

Clyde C. Carr, Chicago, Ill.

Application July 2, 1952, Serial No. 20,449

Term of patent 14 years

(Cl. D44—29)

To all whom it may concern:

Be it known that I, Clyde C. Carr, a citizen of the United States, residing in the city of Chicago, county of Cook and State of Illinois, have invented a new, original, and ornamental Design for a Double Boiler Adapter Ring, of which the following is a specification, reference being had to the accompanying drawings, forming a part thereof, in which

Figure 1 is a perspective view of the double boiler adapter ring showing my new design;

Figure 2 is a cross-sectional view taken on the diameter through Figure 3 and looking in the same direction as Figure 3;

Figure 3 is a side elevational view thereof;

Figure 4 is another side elevational view taken from the left of Figure 3;

Figure 5 is a top plan view thereof; and Figure 6 is a bottom plan view thereof. The double boiler shown in dotted lines is only for illustrative purposes.

I claim:

The ornamental design for a double boiler adapter ring, as shown and described.

CLYDE C. CARR.
